UNITED STATES PATENT OFFICE

157,512

ELECTRIC ROOM HEATER OR SIMILAR ARTICLE

Israel Pass, St. Louis, Mo., assignor to Knapp-Monarch Company, St. Louis, Mo., a corporation of Delaware

Application January 15, 1949, Serial No. 252

Term of patent 14 years

(Cl. D81—19)

To all whom it may concern:

Be it known that I, Israel Pass, a citizen of the United States, and a resident of the city of St. Louis, State of Missouri, have invented a new, original, and ornamental Design for Electric Room Heater or Similar Article, of which the following is a specification, reference being had to the accompanying drawing, forming a part thereof, in which:

Figure 1 is a front perspective view of an electric room heater or similar article, showing my new design;

Figure 2 is an end elevational view thereof;

Figure 3 is a top plan elevational view of the heater; and

Figure 4 is a front elevational view thereof.

I claim:

The ornamental design for an electric room heater or similar article, substantially as shown.

ISRAEL PASS.
